CLAIM

The ornamental design for a garment as shown and described.

DESCRIPTION

FIG. 1 is a front perspective view of a garment showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The evenly spaced broken lines depict stitching that forms no part of the claimed design. The broken line outline of the partial human figure assists in illustrating how the garment may appear when in a position of use and forms no part of the claimed design. The dash-dot-dash broken lines on the surface of the garment depict features of the garment that form no part of the claimed design. The dash-dot-dot-dash broken lines define the bounds of the claim and form no part of the claimed design.
